(57) **CLAIM**

The ornamental design for an electrical connector, as shown and described.

DESCRIPTION

FIG. 1 is a front elevational view of an electrical connector;

FIG. 2 is a top plan view thereof;

FIG. 3 is a bottom plan view thereof;

FIG. 4 is a right side elevational view thereof;

FIG. 5 is a rear elevational view thereof; and,

FIG. 6 is a perspective view of the front and right side thereof.

A left side elevational view of the electrical connector is omitted because it is presented symmetrical to the right side elevational view of FIG. 4.
